Primary Examiner — John Windmuller*Assistant Examiner* — Steven J Czyz(74) *Attorney, Agent, or Firm* — Paul Murty; Smith & Hopen, P.A.(57) **CLAIM**

The ornamental design for a clamping tool, as shown and described.

DESCRIPTION

FIG. 1 is a perspective view of a clamping tool;
 FIG. 2 is a side elevation thereof.
 FIG. 3 is a side elevation thereof.
 FIG. 4 is a top plan view thereof.
 FIG. 5 is a bottom plan view thereof.
 FIG. 6 is a rear elevation view thereof.
 FIG. 7 is a front elevation view thereof; and,
 FIG. 8 is a top plan view of the clamping tool shown in use
 with environment.
 The broken lines depict portions of the article and environment
 that form no part of the claimed design.

1 Claim, 5 Drawing Sheets(56)
